UNITED STATES PATENT OFFICE.

JAMES BAGLEY, OF BEDFORD, MASSACHUSETTS, ASSIGNOR TO ALICE L. PFEIFFER, OF BEDFORD, MASSACHUSETTS.

PILE WIRE.

Application filed March 31, 1927. Serial No. 179,892.

This invention relates to a pile wire used in a loom for weaving pile fabrics and provided with a cutting blade at its outer or free end, adapted to cut loops formed on the wire, 5 when the wire is being withdrawn from the row of loops.

The invention is embodied in certain improvements in the construction of the blade holder which is fixed to the free end of the 10 pile wire, whereby the holder is adapted to firmly secure the blade in its operative position, and permit the quick and convenient removal and replacement of the blade, and in certain improvements in the blade, adapting 15 it to cooperate with certain features of the improved holder.

Of the accompanying drawings forming a part of this specification,—

Figure 1 is a side view, showing the holder 20 separately.

Figure 2 is a side view, showing the blade separately.

Figure 3 is a section on line 3—3 of 25 Figure 1.

Figure 4 is a side view, showing the holder and blade assembled.

Figure 5 is an edge view of the same.

Figure 6 is a section on line 6—6 of 30 Figure 4.

Figure 7 is a section on line 7—7 of 35 Figure 4.

Figure 8 is a section on line 8—8 of Figure 4.

Figure 9 is a section on line 9—9 of 40 Figure 4.

Figure 10 is a view similar to Figure 4, showing certain variations.

Figure 11 is a section on line 11—11 of 45 Figure 10.

The drawings show the parts much enlarged.

The same reference characters indicate the same parts in all of the figures.

12 designates the outer or free end portion 50 of a pile wire, and 13 a flat-sided blade, preferably of the sheet steel wafer type. The holder fixed to the body 12 is formed from a single blank of thin sheet metal, and includes opposed jaws 14 and 15, connected by a neck 55 16 to form a blade-receiving channel. The jaws yieldingly grasp the sides of the blade and are adapted to be sprung apart at their forward ends, to permit the insertion and removal of the blade.

55 The outer end of the jaw 14 has a spoon or

head 17, which is extended beyond the outer end of the jaw 15, and bears on a side of the outer end portion of the blade. The blade projects forward from the outer end of the jaw 15, so that the outer end portion of its outer side is unsupported, and it may be laterally displaced as shown by dotted lines in Figures 8 and 9, from the position shown by full lines in which it is normally held.

The channel formed by the jaws and neck 60 contains a longitudinal back abutment on which the back of the blade 13 bears, to locate the cutting edge 13^a in an operative position above the holder. Said back abutment may be the neck, when the pile wire 12 is relatively narrow. When said wire is wider than the minimum width, the back abutment is formed by a series of members 19, integral with a jaw of the holder and projecting laterally into the channel. Said members are 65 preferably the sides of oblong indentations or bosses, pressed inwardly from one of the jaws, in this instance, the jaw 15, although they may be pressed from either or each of the jaws. The object of the members 19 is 70 to bring the cutting edge of the blade at the proper level or height.

The inner end of the channel formed by the jaws, and the neck 16, receives the outer end of the pile wire 12, and is suitably secured 75 thereto, the neck bearing on the lower edge of the wire. The members 19 extend parallel with the neck, and may be located at any height above the neck required to locate the cutting edge 13^a of the blade above the jaws. 80 Owing to the fact that the members 19 are integral parts of the holder, they provide a blade back abutment which is inseparable from the holder, and does not involve the employment of a separate part inserted in the channel. When the blade back abutment is formed by the members 19, I provide the spoon 17 with a supplemental blade back abutment 20, formed by a boss integral with the spoon, and in alignment with the members 19, 85 so that it supports the projecting forward end portion of the blade back, as shown by Figures 4 and 10.

I provide the spoon 17 with abutment means bearing on the blade at its forward 90 end portion, to confine the blade back against forward and upward movement from its predetermined position on the back abutment. In Figures 1 and 4 I show said abutment means embodied in a boss 21, arranged to 95

bear on the transverse edge 13^b, forming the outer end of the blade, said edge being at right angles with the back edge, and a boss 22, arranged to bear on the outer extremity 5 of the cutting edge 13^a. The bosses 20, 21 and 22, are integral parts of the spoon and present bearing edges projecting from the inner side thereof, slightly more than the thickness of the blade, so that the blade can 10 be readily displaced outwardly, at its outer end, and thus disengaged from the bosses. The boss 21 constitutes an end stop, and the boss 22 a holding-down stop.

In Figure 10 I show the spoon provided 15 with an abutment for the above-described purposes, and composed of a single boss 23, whose bearing edge is inclined and located in position to bear on the transverse edge 13^c, forming the outer end of the blade, said edge 20 being inclined, so that the boss overhangs it, and performs the dual function of an end stop and a holding-down stop.

I provide the inner end portion of the holder with a boss 24, preferably formed 25 like the bosses 21 and 22, and pressed inwardly from one of the jaws into the channel, in position to overhang an inner end portion of the blade, and prevent inward endwise displacement of the blade, and upward displacement 30 of its inner end portion. The transverse edge 13^d forming the inner end of the blade, is preferably inclined, so that the boss 24 overhangs said edge and performs the dual function of an end stop and a holding-down stop. The blade may be positively locked to the holder, to prevent the possibility 35 of its accidental disengagement from the confining means above described. This may be accomplished as shown by Figures 1, 2, 40 10 and 11, by providing the jaws with orifices 26, and the blade with an orifice 27, said orifices registering with each other as shown by Figure 11, when the blade is in its operative position, and inserting and securing a plug 28 45 in the orifices. The plug may be a short stud soldered within the orifices, or it may be formed within the orifices by inserting a filling of melted solder in the orifices, and allowing it to solidify therein by cooling. The 50 plug may be ejected by any suitable means, when the blade is to be removed. The plug is secured wholly within the orifices, so that its ends may be flush with the outer sides of the jaws, as shown by Figure 11. The thickness 55 of the structure is therefore not increased by the plug.

The boss 24 is preferably formed like the bosses 20, 21 and 22, so that it presents a clearly defined edge 24^a (Figure 5), bearing 60 on the inner end portion of the blade, and located wholly within the margin of the jaw on which the boss 24 is formed.

It will be seen that the holder is characterized by a group of spaced apart indentations 65 integral therewith and constituting

abutment members arranged to bear on different portions of the blade margin, and prevent endwise and edgewise displacement of the blade in any direction, until the blade is displaced laterally, as shown by dotted lines 70 in Figure 8. Said abutment members may be formed by a single operation on the blank from which the holder is formed, and do not involve the addition of a part or parts to said blank, so that the holder and the abutment members may be formed in a single piece. 75

The alined indentations 19, formed on one of the jaws and projecting into the channel above the neck 16, to form abutments, bearing on the blade back within the channel and supporting the blade raised above the neck, particularly characterize the invention. The blade-back abutment 20, formed on the spoon 80 in alinement with the abutments formed by the indentations 19, and supporting the forward end portion of the blade back, additionally characterizes the invention. 85

I claim:

1. A pile wire including a body portion, a flat-sided blade, a blade-holder fixed to the body portion and comprising opposed jaws connected by a neck to form a channel and yieldingly grasping the sides of the blade, the channel containing a longitudinal back 90 abutment supporting the blade back and operatively locating the cutting edge above the holder, the jaws and blade being provided with orifices arranged to register with each other when the blade back is in its operative position on the back abutment, and a plug inserted in said orifices, and secured therein, so that its ends are flush with the outer sides of the jaws. 95

2. A pile wire which includes a body portion, a flat-sided blade, whose margin includes a back portion, outer and inner end portions, and a cutting edge, and a sheet-metal blade-holder fixed to the body portion and including opposed blade-grasping jaws 100 connected by a neck to form a blade-receiving channel, one of said jaws and the blade being laterally displaceable, and a spoon formed on the outer end of one of the jaws and bearing on one side of the blade, the 105 holder being characterized by a group of spaced apart indentations integral therewith and constituting abutment members arranged to bear on different portions of the blade margin and prevent endwise and edgewise displacement of the blade in any direction, when the blade is not laterally displaced. 110

3. A pile wire which includes a body portion, a flat-sided blade, whose margin includes a back portion, outer and inner end portions, and a cutting edge, and a sheet-metal blade-holder fixed to the body portion and including opposed blade-grasping jaws 115 connected by a neck to form a blade-receiving 120

channel, one of said jaws and the blade being laterally displaceable, and a spoon formed on the outer end of one of the jaws and bearing on one side of the blade, the holder being characterized by a group of spaced apart indentations integral therewith and constituting abutment members arranged to bear on different portions the blade margin and prevent endwise and edgewise displacement of the blade in any direction, when the blade is not laterally displaced, said members including a row of blade back-supporting members formed on one of the jaws and projecting into the channel above the neck, to bear on the back portion of the blade margin, and operationally support the cutting edge.

4. A pile wire which includes a body portion, a flat-sided blade, whose margin includes a back portion, outer and inner end portions, and a cutting edge, and a sheet-metal blade-holder fixed to the body portion and including opposed blade-grasping jaws connected by a neck to form a blade-receiving channel, one of said jaws and the blade being laterally displaceable, and a spoon formed on the outer end of one of the jaws and bearing on one side of the blade, the holder being characterized by a group of spaced apart indentations integral therewith and constituting abutment members arranged to bear on different portions of the blade margin and prevent endwise and edgewise displacement of the blade in any direction, when the blade is not laterally displaced, said members including a row of blade back-supporting members formed on one of the jaws and projecting into the channel above the neck, to bear on the back portion of the blade margin, and a member formed on the spoon in alignment with the said row and bearing on the back portion of the blade margin, at the forward end of the blade.

5. A pile wire which includes a body portion, a flat-sided blade whose margin includes a back portion, oppositely inclined outer and inner end portions, and a cutting edge, and a sheet-metal blade-holder fixed to the body portion and including opposed

blade-grasping jaws connected by a neck to form a blade-receiving channel, one of said jaws and the blade being laterally displaceable, and a spoon formed on the outer end of one of the jaws and bearing on one side of the blade, the holder being characterized by a group of spaced apart indentations integral therewith and constituting abutment members arranged to bear on different portions of the blade margin and prevent endwise and edgewise displacement of the blade in any direction, when the blade is not laterally displaced, said members including a holding-down member formed on one of the jaws and bearing on the inclined inner end portion of the blade margin, and a holding-down member formed on the spoon and bearing on the inclined outer end portion of said margin.

6. A pile wire which includes a body portion, a flat-sided blade whose margin includes a back portion, outer and inner end portions, and a cutting edge, and a blade-holder fixed to the body portion, and including opposed blade-grasping jaws connected by a neck to form a blade-receiving channel, and abutments adapted to bear on the margin of the blade and confine it against endwise and edgewise displacement in any direction, said abutments including a row of blade-back abutments formed on one of the jaws and projecting into the slot, to support the blade back above the neck.

7. A pile wire as specified by claim 6, the holder including also a spoon projecting from the outer end of one of the jaws, and having a blade-back abutment projecting therefrom in alignment with the abutments on said jaw, to bear on the outer end of the back.

8. A pile wire as specified by claim 6, the holder being made of a single piece of sheet metal, and the several abutments being integral parts of the holder and grouped around the blade margin, so that they collectively oppose edgewise and endwise displacement of the blade in any direction.

In testimony whereof I have affixed my signature.

JAMES BAGLEY.
